ADJUSTABLE CARDHOLDER SUPPORT

Stephen J. Adams, Swoyersville Borough, Luzerne County, Pa., assignor of one-half to Al. J. Kane, Wilkes-Barre, Pa.

Application March 19, 1948, Serial No. 15,885

2 Claims. (Cl. 211—105)

1

The invention relates to an adjustable card support or holder designed for convenient use as a temporary support for a card or other light weight reference material in assembly halls, auditoriums and the like where persons are prone to congregate for observance of various educational, religious, or other social functions.

A principal object of the invention is to provide a card holder or support of sturdy light weight construction which may be readily collapsed to occupy a minimum of space when not in use, and which may be readily manually extended and adjusted as desired for removable attachment to the backs of various types of chairs commonly used in such public gathering places. For example the invention is capable of being used to advantage in playing the game of "Bingo" in church auditoriums, halls and basements. For this purpose the device may be attached to and supported by the back of a chair for use in supporting in substantially horizontal position a "Bingo" card or similar game board for the convenient use of a person occupying the chair immediately in the rear of the chair to which the improvement is removably secured.

The improved device is equally adapted for use to advantage for other comparable purposes or forms of education or entertainment wherein it is desired to support various types of light weight cards, pads, pamphlets, note books or programs for the use and convenience of the person occupying the chair facing the chair back to which the invention is attached.

The improved device is designed to be constructed of light weight sheet metal, plastic or other appropriate and preferably flexible material, and is composed of a minimum number of working parts which when assembled, may be extended for use as a support and thereafter collapse into a rather small space for packaging or storing in a cardboard box or other appropriate protective receptacles.

The material of which the device is constructed is preferably of a character which may be distorted or readily bent into proper form for secure, non-slipping engagement with appropriate portions of chair backs of various and well known types which are commonly found in the described localities where the instant invention is designed to be used for the convenience of the patrons. Also the improvement is designed for economical production in bulk at relatively low manufacturing cost.

Numerous other objects and advantages of the invention will be apparent as it is better under-

2

stood from the following description, which, taken in connection with the accompanying drawings, discloses a preferred embodiment thereof.

Referring to the drawings:

Fig. 1 is a perspective view of a preferred embodiment of the invention in extended position illustrated as removably engaged with or attached to the back of a folding chair of a well known conventional design.

Fig. 2 is a plan view of the holder or support in extended or partially expanded position, also as illustrated in Fig. 1.

Fig. 3 is a side or edge view of the holder.

Fig. 4 is an enlarged detail sectional view on line 4—4 of Fig. 2.

Fig. 5 is a similar view on line 5—5 of Fig. 2.

Fig. 6 is a view similar to Fig. 2 showing the improved holder or support in folded or collapsed position for shipment or storage.

Referring to the drawings the device in its preferred embodiment essentially comprises a pair of similar side supporting members or strip elements 10 and 11 preferably composed of light weight metal or plastic, but which obviously may be constructed of wood or other appropriate light weight material if desired.

At their forward ends the said strips are each bent or extended upwardly as at 12 and thence curved outwardly at 13 to constitute a forward depending terminal extension 14 spaced from the upstanding portion 12, so as to constitute hooks for removable engagement with the back or rail member 15 of a chair C, illustrated for example as of the conventional light weight folding variety.

A series of intermediate interconnected link members 16 are pivotally connected together at 17 in the manner of a lazy tongs, the outer ends of a pair of connected links being in turn pivotally connected as at 18 to the aforesaid side strip members 10 and 11. A second pair of connected link members 16 are respectively pivotally connected as at 19 at their outer ends to the side members 10 and 11 respectively, said latter mentioned pivotal connections 19 being also slidably mounted in elongated slots or recesses 20 formed in the said strip members.

One or more of the said pivotal connections 17, 18, 19 may be of the relatively soft mushroom rivet character to afford sufficient friction to guard against undue undesired looseness in the structure, while permitting its expansion and contraction as desired into extended or folded position.

When the side members 10 and 11 of the holder are moved towards or away from one another to collapse or extend the holder, it will be obvious that the pivotal connections 19 are thus caused to slide within the elongated slots 20 to accommodate the pivotal movement of the links in opposite directions when the device is so manipulated, as will be readily apparent.

When in extended position and attached to a chair back as shown in Fig. 1, the main supporting portion of the device is in substantially horizontal position, also as seen in Fig. 3, to serve as a firm support for a "Bingo" card A or other light weight pamphlet or documentary material, generally indicated by dotted lines in Fig. 1.

Since the side strip members 10 and 11 are preferably formed of relatively flexible or ductile material, it will be apparent that the hook portions 12, 14 at their forward ends may be pressed or manipulated by hand so as to fit over and engage for card or manuscript supporting purposes, different types of chair backs of varying structural configuration but commonly found in churches, assembly halls and other meeting places in conjunction with which the present invention is designed to be employed. For example the improvement is designed to be readily installed for temporary use in a church by hooking the forward end of the support over the rear wall of the pew.

For protective purposes and to insure against scratching or marring the furniture, the forward or hooked ends of the support may be encased if desired in a suitable protective covering of rubber, leather or fabric, as indicated in dotted lines at 21 in Fig. 3.

From the foregoing it will be apparent that the support may be quickly folded or collapsed for transportation, storage or packaging within a relatively small space, as best shown in Fig. 6. Also when laterally extended into its supporting position the holder may be variably expanded as desired within limits permitted by the movably mounted pivoted links so as to most effectively fit and conform itself to chair backs of varying widths. For the purpose of temporarily holding the device in its desired extended position, one or both of the pivotal connections 19 may constitute a bolt or screw member 22 having threadable engagement with a wing nut 23 as best illustrated in Fig. 4 to releasably clamp the device against undesired expanding or contracting movement within the side member slots or recesses 20 when the holder has been extended to its desired card supporting position in accordance with operating conditions.

While the supports 10 and 11 and links 16 have been illustrated in the form of flat strip elements, the improvement contemplates forming these elements of various thickness or light weight channeled I-beam, T-bar or L-bar configuration in cross section, as will be obvious in order to meet various manufacturing requirements or conditions.

When in assembled position on a chair back it will be apparent that the spaced flexible and yieldable upstanding and depending hook portions 12 and 14 of the strip members 10 and 11, will engage opposite surfaces of the chair back in such manner as to prevent appreciable tilting movement of the adjustable device from its card supporting position, and is effectively held by such hooks from other than intentional displacement or lifting from the chair or other support. When employed for the herein described desir-

able purpose of supporting a "Bingo" card or board, the player occupying the chair immediately in the rear of the chair to which the improvement is attached, may conveniently manipulate the movable checker pieces in accordance with the progress of the game without being subjected to the objectionable necessity of holding the card upon the knees or lap while the game is in progress.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

What is claimed is:

- 20 1. A card holder for chair backs and church pews, comprising a pair of parallel side members, each member having at one end thereof an integral angularly extending hook, the angle being other than a right angle, said hook consisting of continuously connected upstanding and depending portions, an elongated slot in each side member at the end thereof adjacent said hook, pairs of link elements pivotally connected at their centers, each pair of link elements being also pivotally connected at one end thereof, the ends of one pair of link elements being pivotally connected to the ends of said side members remote from said hook, the ends of the other pair of link elements being slidably and pivotally connected to said side member slots.
- 25 2. A card holder for chair backs and church pews, comprising a pair of parallel side members each having an integral angularly extending hook at one end thereof, said hook including continuously connected upstanding and depending portions, an elongated slot in each of said side members at one end thereof, a plurality of pairs of link elements each composed of individual links pivotally connected together intermediate their opposite ends, one link of each outermost pair of link elements being pivotally secured at its outer end to the end of the adjacent side member remote from said slot, the corresponding outer ends of the remaining links of each outermost pair of link elements being slidably and pivotally connected to the aforesaid slots respectively, whereby said card holder may be extended and removably attached by said hooks to a chair back or church pew and removed therefrom and laterally compressed to collapse the holder into compact position.
